AUTOMOBILE WINDOW SASH MECHANISM

Daniel L. Chandler, Somerville, Mass., assignor to Aresee Company Inc., Salem, Mass., a corporation of Massachusetts

Original application September 3, 1937, Serial No. 162,283. Divided and this application September 24, 1937, Serial No. 165,536

3 Claims. (Cl. 268—126)

My present invention relates to automobile window sash mechanisms, and more particularly to improved window sash elevating mechanism.

The principal object of my invention is an improved automobile window sash mechanism;

Another object is a parallel elevating and lowering mechanism for sliding window sashes;

Still another object is the combination of a counter-balanced parallel elevating and lowering mechanism for sliding window sash, and

Other objects and novel features comprising the construction and operation of my device will appear as the description of the same progresses.

In the drawing illustrating the preferred embodiment of my invention:

Fig. 1 is a side elevation of the apparatus removed from an automobile door;

Fig. 2 shows the opposite side of the elevating and lowering mechanism, as viewed in Fig. 1, a portion of the sash pane being broken away for convenience, and

Fig. 3 shows a cross section taken on the line 3—3 of Fig. 1.

In Fig. 1 I have indicated at 10, in broken lines, a panel of the door of an automobile. At 11 I have indicated the opening of the window, also in broken lines, the window being shown in a closed position. The sash pane 12 of the window is provided with a bottom channel member 13, as is usual in window construction of this type. At two separated points on the channel member 13 I have attached, as by welding, two right-angled bracket members 14 and 15.

At 16, I have indicated a curved plate member which is bolted at 17 to the panel member 10. The entire mechanism is carried on the bolts 17.

The apparatus shown in the drawing is provided with certain locking mechanism inclosed within the casing 18 which cooperates with the lever 19 and the toothed periphery 20 on the fixed plate 16. This locking apparatus is fully disclosed in my copending application entitled Automobile window sash lock, filed September 3, 1937, Serial Number 162,283, in which the mechanism with which this application is concerned is also disclosed. This is a division of the mentioned application. For the purposes of the present application, the fixed plate 20 may be of any shape and without the toothed periphery 20. Also the lever 19 may be considered as being attached to the bell-crank lever 21 in a permanent manner.

Through the plate 16 is journaled a shaft 22 the front end of which is slotted to receive the counterbalance spring 23 the other end of which

is anchored around the pin 24 fixed in the plate 16. The other end of the shaft 22 is preferably squared on the portion which protrudes beyond the plate 16 and is fitted in a squared opening in the lever 21. A washer 25 and machine screw 26 are provided to hold the shaft collar 27 tightly against the plate 16 thereby maintaining the lever 21 and plate 16 in contact with each other.

At 28 I have provided a second bell-crank lever reversely positioned with respect to the bell-crank lever 21. The long leg of the lever 28, as shown at 29, is slidably pivoted at 30 in the horizontal slot 31 located in the bracket 14. The bracket 15 is similarly provided with a horizontal slot 32 which is adapted to receive a pivot pin 33 which is fixed in the lever 21 and journaled through the lever 28. A top extension member 35 is located on the lever 28 and is adapted to bear against the vertical leg of the bracket 15 for the purpose of maintaining the apparatus in a braced relationship with the plate 16 thereby preventing such apparatus from becoming cramped when in operation. Below the shaft 22 and a part of the plate 16 I have provided a hanger 36. A lower arm 37 is provided on the lever 28. The connecting lever 38 is pivoted at 39 to the lever leg 37 on one end and at 40 in the hanger 36. The center distance between the shaft 22 and pivot pin 40 is equal to the distance between the pin 33 and 39 in the lever 28. Also the vertical axis taken through the centers of the pins 33 and 39 is parallel to the vertical axis of the centers of the shaft 22 and pin 40.

When the horizontal lever 45 which is pivoted at 46 to the lever 19, is pulled to the right or left, the lever 21 applies force at the pin 33 and elevates or lowers the glass 12 thereby opening or closing the window, as the case may be.

With window glass which is wider in a horizontal direction than in a vertical direction it is necessary that the sash pane, as 12, be moved up and down in a perfectly vertical direction otherwise it will tilt to one side or the other and jam in the slide-ways of the door frame. In my present arrangement the parallel bar 38 maintains the horizontal leg of the lever 28 in a horizontal plane at all times and the forces exerted primarily on the pin 33 are partially transposed to the pin 30 in the bracket 14 thereby giving the glass 12 a vertical movement with equal forces applied at two separate points. An illustration of the change in position of the mechanism is shown in dot-and-dash lines in Fig. 1 showing the lowermost position of the apparatus.

Having thus described my invention what I claim as new is:

1. An improved automobile window sash elevating mechanism comprising in combination, a plate fixed to the frame of said window, slotted brackets attached to the bottom edge of said sash, said slots being elongated in a horizontal plane, an inverted L member slidably engaged in said slots, the long side of said L member being provided with studs adapted to engage in said slots, an extension member attached to said L member at a point above its right-angle corner, said extension member being adapted to bear against the side of the respective bracket, a bell-crank lever one leg of which is pivoted on the stud located at the said right-angled corner of said L member, the other end of said bell-crank lever being connected to a horizontal hand operating lever, said bell-crank lever being pivoted to said fixed plate, a parallel lever pivoted to the depending end of said L member at one end and the opposite end being pivoted to said fixed plate.
2. An improved automobile window sash operating mechanism comprising, a plate fixed to the frame of said window, a bell-crank lever pivoted to said plate, horizontally slotted brackets attached to the bottom edge of said sash, said slots being elongated in a horizontal plane, an inverted L member slidably engaged in said slots, the long side of said L member being provided with studs adapted to engage in said slots, said extension member attached to said L member at a point above its right-angle corner, said extension member being adapted to bear against the side of the respective bracket, a bell-crank lever one leg of which is pivoted on the stud located at the said right-angled corner of said L member, the other end of said bell-crank lever being connected to a horizontal hand operating lever, said bell-crank lever being pivoted to said fixed plate, a parallel lever pivoted to the depending end of said L member at one end and the opposite end being pivoted to said fixed plate.
3. Improved operating mechanism for automobile door window sashes comprising, a bell-crank lever pivoted to said door, horizontally slotted brackets attached to said sash, a right-angled lever comprising a horizontal and vertical arm, the horizontal portion being slidably pinned in said slots, the vertical arm end of said right-angled lever being pivoted to one end of said bell-crank lever, a parallel lever pivoted to one end of said vertical portion of said right-angled lever and said door, a guide member located on said right-angled lever adjacent the vertical end portion and adapted to engage one of said slotted brackets for the purpose of stiffening said right-angled lever.
